Primary Examiner — Kimberly Barnes*Assistant Examiner* — Sarah A Nguyen(74) Attorney, Agent, or Firm — Jose Cherson Weissbrot(57) CLAIM

The ornamental design for a bird feeder cover, as shown and described.

DESCRIPTION

FIG. 1 is a top perspective view of a bird feeder cover, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view of the bird feeder cover, shown in an environment of use.

The broken lines in FIG. 8 depict environmental subject matter that form no part of the claimed design.

1 Claim, 6 Drawing Sheets(56)
